UNITED STATES PATENT OFFICE.

LOUIS H. WELLENSIEK, OF HOUSTON, TEXAS.

DRILLING APPARATUS.

Application filed October 19, 1920. Serial No. 417,975.

To all whom it may concern:

Be it known that I, LOUIS H. WELLENSIEK, a citizen of the United States, residing at Houston, in the county of Harris and 5 State of Texas, have invented certain new and useful Improvements in a Drilling Apparatus, of which the following is a specification.

This invention relates to new and useful 10 improvements in a drilling apparatus.

One object of the invention is to provide an apparatus of the character described, to be used in drilling wells where the formation encountered is shifting and has a tendency 15 to cave in and fill up the hole.

Another object of the invention is to provide a drilling apparatus capable of handling two concentric strings of pipe in the hole at the same time, the outer string or 20 casing, being provided to hold back the shifting strata of the earth and the inner string, or drill stem, being provided to drill the hole in advance of the casing, both of 25 said strings being rotated through the instrumentalities of a rotary at the ground surface.

With the above and other objects in view, the invention has particular relation to certain novel features of construction, operation 30 and arrangement of parts, an example of which is given in this specification and illustrated in the accompanying drawings, wherein:

Figure 1 is a vertical, sectional view of 35 the upper half of the swivel swedge employed.

Figure 2 is a side view thereof.

Figure 3 is a top view of the swivel swedge.

Figure 4 is a vertical, sectional view of 40 the lower half of the swivel swedge.

Figure 5 is a side view thereof.

Figure 6 is a view in elevation showing 45 the apparatus in position for drilling.

Referring to the drawings and particularly to Fig. 6 wherein like numerals of reference designate similar parts in each of the figures the numeral 1 refers to a rotary of conventional construction, which is

50 mounted upon the derrick floor 2 and which is driven by the pinion 3, fixed on the inner end of the shaft 4, in the well known manner. The numeral 5 designates the surface casing whose upper end is approximately

flush with the ground surface and which extends down into the bore a comparatively short distance, usually about two hundred feet. The numeral 6 designates the depth casing which is gradually let down into the bore as drilling progresses and which 60 usually extends down to the oil-bearing strata when the well is completed. The numeral 7 designates the drill stem, to the lower end of which the drilling tool is attached, and by means of which said drilling tool is rotated to deepen the bore. As illustrated in Figure 6, the drilling tool embodies a boring bit 18 and expansible or underreaming blades 19, so that the well 70 may be drilled simultaneously with a widening or underreaming operation to permit the downward movement of the depth casing 6. I have designed a tool adapted for this two-fold function, but a detailed description thereof is omitted from the present application because the subject matter is properly contained in a divisional application Ser. No. 596,749, filed Oct. 25, 1922. The depth casing 6 and the drill stem 7 are 75 made up of joints of approximately the same length which are connected by means of suitable couplings.

In drilling, water is forced under pressure down through the drill stem to the point of the bit and returns up between said stem and the depth casing. This water carries away the cuttings from the drilling tool and keeps the depth casing cleansed of mud and other detritus. In order to prevent the water from returning to the ground 80 surface on the outside of the depth casing, the casing head 11 has been provided. The casing head 11 as indicated in Figure 6 is preferably provided with means (not shown) adapted to permit the depth casing 85 couplings to pass through the casing head and at the same time prevent the discharge of water from the depth casing. A detailed description of this expansible member is omitted from the present specification, as it per se constitutes subject matter for a divisional application Ser. No. 596,749, filed 90 Oct. 25, 1922.

The upper joint 26 of the drill stem is 95 commonly designated a grief stem inasmuch as the gripping means, carried by the rotary table is connected to it and the entire stem thus rotated. In practice, this grief

stem or joint should be made somewhat longer than the other joints of the stem, and is always connected to the top of the stem so as to thereby readily connect it with 5 the pipe gripping means carried by the rotary table. It is to be here noted that in making a well the drilling may be carried on by the usual rotary process involving the use of a single drill stem to which the 10 bit is attached and which is rotated by the ordinary rotary and the apparatus herein described is employed when formations are encountered which are composed of quicksand or other shifting or caving formations, 15 and thereafter the depth casing and the drill stem are rotated simultaneously and descend in unison until the treacherous stratum has been passed after which drilling may proceed in the usual way.

20 The depth casing passes through the central opening of the rotary table and may be connected thereto, by any suitable pipe-gripping device well known to those familiar with the art of drilling. As shown in 25 Figure 6 the wedge-shaped slips 12 are employed for this purpose, and the casing 6 is thereby rotated as the rotary table turns.

This casing is connected to and rotates the drill stem 7 through a connecting mechanism shown in elevational view in Figure 6 and illustrated in detail in Figures 1 to 5 inclusive. A tubular casing 27 is connected to the upper end of the casing 6 by means of a coupling 28 which is locked 30 against unscrewing by means of the locking ring 29. This ring has an internal recess to receive the collar 28, as shown in Figure 4. Above said collar the ring has the inward extensions 30 which rest in notches 31 in the 35 swivel swedge casing 27, and beneath the collar 28 the locking ring 29 has internal pipe-engaging teeth 29a which engage with the casing 6.

The swivel swedge casing is formed of 45 upper and lower sections which are anchored together by means of set bolts 32, and the upper section is formed with a stuffing box 33', through which the drill stem 7 passes, and above said stuffing box said 50 casing 27 is formed with upwardly converging walls forming bearing faces for the pipe-engaging jaws 33. These jaws are mounted in the swivel swedge casing by means of the links 34, 34 and 35, 35, said 55 links being pivoted at their inner ends to said jaws and working through suitable slots 36, 36 on the pin bearings 37, 37 and 38, 38, respectively. The purpose and operation of these jaws will be hereinafter 60 more specifically set forth.

The upper end of the swivel swedge casing 27 has opposing transverse bearings 39, 39 in which the respective shafts 40, 40 rotate. The shafts 40 carry the pipe-engaging grip 65 rings 41, arranged on opposite sides of the

drill stem and provided to engage therewith, as shown in Figure 3. The ends of the respective shafts 40 have their bearings in opposing jaws 42 which may be adjusted toward and from each other through the medium of adjusting screws 43, 43. Each adjusting screw is connected at one end to one of the jaws 42 and passes through a bearing in the other jaw, and threaded onto the free end thereof is the adjusting hand wheel 44. By turning these hand wheels in one direction the gripping device may be caused to engage with the drill stem, and when turned in the other direction may be released therefrom.

In drilling, the rotary table is connected to the depth casing 6 and the same is thereby rotated and the rotation thereof is transmitted through the swivel swedge casing and the pipe-gripping rings 41 to the drill stem, and said depth casing and drill stem are thereby rotated in unison. The swivel swedge casing 27 has opposing connections 45 and 46 for the quick attachment and removal of the hose connections 47, to which the discharge hose may be attached, said hose being provided for conducting away the slush which is delivered up between the casing 6 and drill stem 7.

As drilling progresses the drill stem and depth casing gradually descend and from time to time additional joints must be connected to the upper ends thereof. When it is desired to connect an additional joint suitable mechanism is provided for securing the drill stem and depth casing in position while the additional joints are being attached. With the apparatus in position the additional joints of drill stem and casing may be attached in any suitable manner, as for example, as follows:—Near the derrick there is always provided a hole of sufficient depth to take a joint of the pipe and of sufficient diameter to receive the casing. This hole is usually cased and has a platform arranged above it and to this platform there is fastened a slip holder of conventional construction having preferably two sets of slips, one to fit the casing and the other to fit the drill stem. A joint of drill stem is first 110 picked up and lowered into this hole by the employment of the apparatus provided for this purpose and common to rotary rigs. The grief stem 26 is next attached to this joint of the drill stem. It is to be here noted that the mechanism for connecting the drill stem with the casing and which drives said stem, and which is illustrated in Figures 1 to 5 inclusive, remains attached to the grief stem being connected thereto by the jaws 33. The grief stem is screwed onto the joint of pipe and then both are picked up as a unit and swung in the derrick. A joint of casing 115 is then let down into said hole and is held suspended therein by the slips. The grief 120

125

stem is again elevated and together with the joint of pipe attached to it is lowered through said casing until the swivel swedge casing 27 comes to the top of the depth casing 6, and they are connected by means of the collar 28, and the locking ring 29 is then put in place. The grip rings 41 are then tightened up against the drill stem and the discharge hose is hooked onto the connections 47. The joints as thus connected are now picked up and swung over the hole and the drill stem is connected up. The additional joint of casing is connected onto the depth casing and the apparatus is then ready for drilling. It is to be here noted that it is preferable to have the grief stem approximately ten feet longer than the average joint of drill stem and to have the pressure hose through which water is forced down into the bore of sufficient length so that the grief stem, with one joint of drill stem connected thereto, can be picked up clear of the rotary table. The rotary is now started and the drill stem is gradually lowered until the bit is somewhat below the casing. The drill stem should be now elevated slightly and as elevated the extended ends of the links 34 should be depressed so as to carry the jaws 33 into engagement with the stem. The swivel swedge will thereby be elevated with the stem. The mechanism for securing the depth casing on the rotary table is now removed and drilling again started.

While drilling water is being forced under pressure down through the drill stem and the reaming blades 19 are caused to expand and ream out the bore under the casing so as to permit the casing to descend as the drilling operation progresses. This operation may be continued until it becomes necessary to add an additional joint to the top of the drill stem and the casing. When another joint must be added the depth casing is again secured, as before explained, and the drill stem is lowered slightly, causing the jaws 33 to release. The drill stem may then be picked up clear of the bottom and the pump shut off. The locking ring 29 is removed and the swivel swedge casing is uncoupled from the depth casing. The grief pipe is detached from the drill stem and an additional joint of casing and stem are made up and attached, as above explained, and drilling continues until the shifting stratum is passed. The special equipment herein described may then be laid aside and the drilling continued with the ordinary drill stem and bit in the usual manner.

Apparatus of preferred form has been shown and described for the purpose of showing one way in which this invention may be practiced, but the inventive thought upon which this application is based is broader than its illustrative embodiment

thereof and no limitations are therefore intended other than those imposed by the appended claims.

What I claim is:—

1. In well drilling apparatus, an outer 70 casing adapted to be let down in a well bore, a drill stem within said casing, a substantially cylindrical member mounted upon the outer casing, pipe gripping means carried by said cylindrical member and adapted to engage the drill stem in such manner as to prevent a longitudinal movement as between said drill stem and outer casing and pipe engaging means carried by said cylindrical member whereby a rotary movement imparted to the outer casing may be transmitted to the drill stem. 75

2. In apparatus adapted to connect two concentric strings of pipes and rotatably support same in a well bore, a casing adapted to be mounted upon the outer pipe, adjustable gripping members mounted within said casing and adapted to engage the inner pipe in such manner that the outer pipe may be supported upon the inner and adjustable means mounted in said casing and adapted to so engage the inner pipe that a rotary movement imparted to one of the strings of pipe may be transmitted to the other. 80

3. In apparatus adapted to connect two concentric strings of pipes and rotatably support same in a well bore, a substantially cylindrical member adapted to be mounted upon the outer pipe and the interior of which is formed with a flared portion, gripping members adjustably mounted within said flared portion and adapted to engage the inner pipe in such manner that one string of pipe may be supported upon the other and connecting means mounted in said cylindrical member and adapted to so engage the inner pipe that a rotary movement may be transmitted from one string of pipe to the other. 100

4. In well drilling apparatus adapted to connect two concentric strings of pipe and rotatably support same in a well bore, a substantially cylindrical member adapted to be mounted upon the outer pipe, adjustable gripping members mounted in said cylindrical member and adapted to engage the inner pipe in such manner as to prevent a longitudinal movement of the pipes with respect to each other and adjustable gripping means mounted in said cylindrical member and adapted to transmit a rotary movement from one pipe to the other. 115

5. In a well drilling apparatus, the combination with two concentrically arranged strings of pipe of a head designed to fit over and rest upon the upper end of the outer pipe and wedge-shaped slips fitted within the head and engaging with the inner pipe to support the outer pipe. 125

4

6. In a well drilling apparatus, an outer casing adapted to be let down into the well bore, a drill stem within said casing, a rotary table provided with a central opening to receive said casing and stem, an operative connection between said table and casing, a swivel swedge connected to said casing and through which said stem extends, pipe-gripping means carried by said swedge and adapted to engage with said stem and rotate the same as the casing rotates, adjustable pipe-engaging jaws carried by said swivel swedge and provided to engage with the drill stem to support the casing on the drill stem.

7. In a well drilling apparatus, a casing adapted to be let down into a well bore, a drill stem within the casing, a rotary table adapted to be connected to and rotate said casing, a device for connecting said casing with the drill stem, whereby the latter is rotated by the former, a coupling connecting said device to said casing and a locking collar surrounding said coupling and attached to said casing and to said device whereby the latter is prevented from unscrewing from the former while the casing is being rotated.

8. In hydraulic well drilling apparatus adapted to connect two concentric strings of pipe and rotatably support same in a well bore, a substantially cylindrical member adapted to be mounted upon the outer pipe,

adjustable gripping members mounted in said cylindrical member and adapted to engage the inner pipe in such manner as to prevent a longitudinal movement of the pipes with respect to each other and adjustable gripping means mounted in said cylindrical member, and a stuffing box mounted within said cylindrical member adapted to prevent the passage of fluid from the outer pipe.

9. In hydraulic well drilling apparatus adapted to connect two concentric strings of pipe and rotatably support same in a well bore, a substantially cylindrical member adapted to be screwed onto the upper end of the outer string of pipe, adjustable gripping members mounted in said cylindrical member and adapted to engage the inner pipe so as to prevent relative longitudinal movement as between the outer and inner pipes, adjustable gripping means mounted in said cylindrical member and adapted to transmit a rotary movement from one pipe to the other and locking means arranged to prevent the cylindrical member from unscrewing when the strings of pipe are rotated.

In testimony whereof I have signed my name to this specification in the presence of two subscribing witnesses.

LOUIS H. WELLENSIEK.
